UNITED STATES PATENT OFFICE.

ANDREW GREENER, OF COLUMBUS, OHIO.

WASHING-MACHINE.

SPECIFICATION forming part of Letters Patent No. 248,450, dated October 18, 1881.

Application filed March 2, 1881. (No model.)

To all whom it may concern:

Be it known that I, ANDREW GREENER, a citizen of the United States, residing at Columbus, in the county of Franklin and State of Ohio, have invented new and useful Improvements in Washing-Machines, of which the following is a specification.

My invention relates to improvements in washing-machines operated by a rocking motion of the tank; and the objects of my improvements are to provide for a more effective cleansing of the clothes as they are carried with the water back and forth in the tank; to provide for a rubbing action upon the clothes in such movements; to afford facilities for heating the water in a rocking tank and during the operation of washing; and to provide means by which the tank is maintained in position and rocked from the same point on the bed, whereby increased force and velocity are given to the clothes. The tank is provided with an elevated corrugated or ribbed surface arranged on the bottom and in the middle of its length, and it is preferably perforated, so that while serving as a rubbing-board it also serves to project the water out from beneath it in streams upon the clothes by the motion of the tank, and thus aid in cleaning the clothes.

Referring to the accompanying drawings, Figure 1 represents my improved washing-machine in elevation; Fig. 2, a vertical longitudinal section; Fig. 3, a cross-section of the same, taken through the movable pivots of the tank; and Fig. 4, a partial sectional view of the tank, showing more clearly the central raised, arched, corrugated, and perforated rubbing-surface and its hinged flaps.

In the drawings I have shown two washing-tanks carried by the same rockers; but one only may be used, or more than two may be used, if desired. I may also dispense with the furnace, and prefer to do so in machines constructed for family use; but for laundries, where washing is constantly done, the furnace is preferable. The washing-tank is mounted upon rockers *a a*, connected with each end of the tank, and operating upon a suitable bed-frame. The tank I prefer to make from fifteen to eighteen inches deep, having a width of one foot and a length of five feet, and of any suitable material. The bottom, for about two feet and a half of its length, is straight, or nearly so, terminat-

ing in upwardly-inclined or curved ends *b b*, which are extended into raised curved parts *c c* at each end of the cover, leaving the middle 55 thereof on a level with the top of the tank, and at which point the cover has a raised open curb, *d*, fitted with a cover, and through which the tank is supplied with water and clothes. When several of these tanks are used they are placed 60 side by side, and of the same or different sizes. Hand-rods are provided at each end, by which to operate the tank.

Centrally upon the bottom of the tank is secured a raised perforated rubbing-surface, *e*, of curved or angular form, leaving a space, *f*, beneath it for the flow of the water, and having its top surface corrugated or ribbed. It may be of sheet metal, and in the rocking of the tank the clothes are thrown upon this ribbed surface, and in passing over it they are more or less rubbed, while the pitching of the tank causes the water to be projected in streams from the perforations in said surface upon the clothes, and thus greatly assist in cleansing them. The relation of this rubbing-surface to the raised curved ends of the cover is such that the clothes will be carried up into the spaces of the cover and pitched over directly upon said surface and carried over it back and forth 80 by the rocking action of the tank. The perforations must be of a size to allow the water to pass freely from the ribbed surface as the clothes are washed over it; and in addition I may provide the opposite ends of this rubbing-surface with hinged flaps *g*, so as to open and close alternately and let the water flow out from the space *f* upon the clothes in the direction they are moving over the rubbing-surface, thus producing a very effective cleaning action 90 merely from the force with which the clothes are carried from one end of the tank to the other with the water. The full effect of the raised rubbing-surface is obtained by the dashing of the clothes upon it from each end of the 95 tank, and in their being swept back and forth over it. It may be of stepped or inclined form; but I prefer the semicircular form shown.

In this style of rocking washer I find it necessary, to obtain the best results, that the tank should be held upon the bed at the point from which it is rocked, and for this purpose I provide the rockers with grooved rolls *h*, which, in connection with open fixed guides *i*, rising from the

bed, serve as movable pivots to the rockers. The grooved rolls are mounted upon the ends of a cross-bar of the rockers, or in any suitable way, and they rock within the guides, rising and falling on the opposite sides thereof with the movements of the rockers, and thus form rocking pivots, holding the rockers at one point upon the bed, whether the latter be curved or straight. This, while giving the advantage of holding the rockers in one place upon the bed, serves to give greater force and velocity in the water and clothes, and to dash them more violently about than could be obtained from a vibrating movement from points of suspension, or from a rocking action in which the rockers travel over and upon a curved bed without centrally-confining points. The guides are of V shape to give rocking freedom to the rolls, and the latter by their deep grooves serve to hold the rockers from lateral displacement. These movable rocker-pivots also render it much easier to operate the machine.

In using the furnace A it is attached to and depends from the under side of the tank and immediately under the rubbing surface, and the top plate, j, of the furnace forms a part of the bottom of the tank and serves to heat the water therein. The bottom of the tank, when made of wood, does not join the top plate of the furnace, but is cut away, and the furnace is secured to a separate plate, k, to which the rubbing-surface may also be secured with water-tight joints.

The furnace is placed crosswise the bottom of the tank or tanks, and may be of any suitable form and construction suited for a rocking motion with the tank, thus giving the advantage of heating the water in a rocker-washer. The furnace carries a smoke-pipe, l, at one end, and its top plate may be corrugated.

In using more than one tank the clothes may be changed from one to the other and into clean water.

As the tank-rockers operate from the rolls h, the upwardly-inclined sides b b and the centrally-depressed top are caused to direct with considerable force the clothes upon the arched rubbing-surface e at every rocking throw of the water in the tank, and thereby effect a more efficient rubbing action of the clothes over the rubbing-surface, so that the functions of these parts co-operate to facilitate the washing.

I claim—

1. The washing-machine herein described, consisting of a rocking tank having a flat bottom provided with a central raised, arched, corrugated, or ribbed surface, substantially as described, for the purpose specified.

2. In a washing-machine, the rocking tank having a flat bottom provided with a central raised, arched surface, e, which is both corrugated and perforated, and forms an inclosed bottom space, f, substantially as described, for the purpose specified.

3. A rocking-tank washing-machine constructed substantially as described, and having a centrally-arranged raised rubbing and perforated bottom surface provided with opposite end-hinged flaps, substantially as described, for the purpose specified.

4. In a washing-machine having a tank mounted upon rockers a, provided with the centrally-arranged rocking rolls h h, the said tank having centrally-arranged, raised, arched, corrugated, and perforated surface e, forming the inclosed space f, the upwardly-inclined ends b b, and a centrally-depressed top, all constructed substantially as described, for the purpose specified.

In testimony whereof I have hereunto set my hand in the presence of two subscribing witnesses.

ANDREW GREENER.
